UNITED STATES PATENT OFFICE

2,432,749

APPARATUS FOR COOLING AND
DISPENSING ARTICLESFred Glassford, Royal Oak, Mich., assignor to
Chrysler Corporation, Highland Park, Mich., a
corporation of Delaware

Application January 14, 1944, Serial No. 518,275

4 Claims. (Cl. 34—65)

1

This invention relates to improvements in apparatus for controllably chilling articles.

An object of the invention is the provision of improved apparatus for facilitating the progression by gravity of articles through a predetermined course in a chilling chamber and the dispensing of the same from the chamber.

Another object of the invention is to facilitate the progression by gravity of articles through a chilling chamber by reducing the amount of moisture carried into the chamber as an incident to the admission of articles thereto.

A further object of the invention is the provision in connection with a dual trackway for guiding articles through a chilling chamber of improved means for dispensing articles from such trackways for discharge from the chilling chamber.

A still further object of the invention is the provision of means for adjustably controlling operation of the dispensing means and more particularly to provide a relatively positive power-operated mechanism for effecting operation of the dispensing means in conjunction with means for variably retarding operation of the dispensing means under the influence of the power-operated mechanism.

Other objects and advantages of the invention will be more apparent from the following description taken in connection with the accompanying drawings, in which:

Fig. 1 is a vertical sectional view of a cooling unit embodying the invention.

Fig. 2 is a view partly in section showing a heating chamber, trackways and hopper associated with the cooling unit of Fig. 1.

Fig. 3 is an enlarged fragmentary view of a part of the trackways viewed as indicated by the line 3—3 of Fig. 2.

Fig. 4 is a fragmentary plan view, with parts broken away and in section to particularly illustrate the dispensing means and parts of the control therefor, the view being located substantially as indicated by the line 4—4 of Fig. 1.

Fig. 5 is an enlarged sectional view taken on line 5—5 of Fig. 4.

Fig. 6 is a fragmentary section taken on line 6—6 of Fig. 5.

Fig. 7 is a side elevational view, mainly in section, taken on line 7—7 of Fig. 4.

Fig. 8 is a top plan view, taken as indicated by line 8—8 of Fig. 2, parts being broken away and in section.

Fig. 9 is a view, partly in section, taken as indicated by line 9—9 of Fig. 8.

2

Fig. 10 is an enlarged transverse section of the trackways taken on line 10—10 of Fig. 1.

Fig. 11 is a fragmentary enlarged sectional view taken on line 11—11 of Fig. 1.

Fig. 12 is an enlarged sectional view taken on line 12—12 of Fig. 1.

Referring to the drawings, the invention is illustrated and described in connection with a refrigerator box 15 having a cooling or chilling chamber 16, the box having inner and outer walls 17 and 18, respectively, between which is a suitable insulating material 19, a removable cover 20 and a base 21. The requisite temperature of the chamber 16 may be provided in any well known manner, as by the circulation of a suitable refrigerant in the well known manner or by deposit of solid carbon dioxide 16' in the chamber 16.

The cover 20 has an inlet opening 22 and a suitable outlet opening 23 is provided in the base wall 21. Extending through the inlet opening 22 and in a circuitous path through the chamber 16 to the bottom of the chamber is a pair of trackways, generally designated by the numeral 24 for guiding articles to be cooled or chilled from a receptacle 25 through a heating chamber 26 at the inlet opening 22, thence through the chamber 16 for subsequent discharge through the outlet opening 23. Articles to be chilled are fed from the receptacle 25 to the single trackway-forming part 27 communicating with a second part 28 flared at the outlet end thereof as shown in Fig. 3 which outlet end has a divider 29 to provide a pair of branches. Connected with the branches so formed are individual trackway-forming parts 30 and 31 each of which has a slot therein forming the trackway, as shown in Fig. 3. The parts 30, 31 are so deflected one relative to the other as to lie in back-to-back relation and thus-wise extend into the heating chamber 26 and this relation exists throughout the trackways.

A trackway-forming part 32 has one end thereof disposed in the heating chamber 26 and connected with the parts 30 and 31, the part 32 having slots 33 and 34 therein, as shown in Figs. 2 and 9, respectively, registering with the slot in the parts 30 and 31 for receiving articles therefrom. The part 32 extends through the opening 22 into the chamber 16 and each slotted side face is covered by a plate 35, as shown in Fig. 8. For support, the part 32 is secured to one of a plurality of vertically spaced bands 36 carried by the wall 17.

Each trackway intermediate the part 32 and a

point adjacent the bottom of the chamber 16 is provided by a pair of spaced slotted members 37 opening one toward the other, each adjacent pair being connected by an intermediate track-forming part 38 secured to an adjacent band 36 and having slots 38 and 40 therein, as shown in Fig. 11, constituting trackways.

Intermediate the aforesaid trackways as thus provided and the outlet opening 23 and within the chamber 16 is a casing structure, generally designated by the numeral 41, containing means for dispensing cooled articles to the outlet opening. This structure includes a pair of opposed side walls 42 and a divider 43 therebetween and so spaced therefrom as to provide a pair of passageways 44 and 45 respectively registering with the trackways, formed as heretofore described and designated as 46 and 47 in Fig. 4, for receiving objects therefrom. The casing includes an enlarged section extending into a trough in the bottom wall 21 and so shaped as to receive an oscillatable dispensing wheel 48 disposed in an opening in the divider 43.

At the side of the wheel 48 opposite the passageways 44 and 45 there is a further dual trackway provided by a part 49 having a reduced end extending into the casing structure 41. To provide the trackways, the part 49 has a longitudinally extending slot 50 formed in each of its opposite side faces, as shown in Fig. 12, each such slot being covered by a plate 51. The plates and part 49 extend through the outlet opening 23 into a box-like structure 52 from which the chilled objects are removed for use, the part 49 and plates 51 being cut away, as shown in Fig. 1, to facilitate removal of articles therefrom.

The dispensing wheel 48 has a recess 53 shaped as shown in Fig. 1 formed in one side face thereof and a corresponding recess 54 in the opposite side face, the recess 53 registering with the passageway 44 when the wheel is in its illustrated position for receiving an article therefrom and the recess 54 registering with one of the adjacent slots 50 in the member 49 to discharge an article thereto. The wheel 48 is mounted for oscillatory movement to a second position wherein the recess 53 is brought into registration with the other slot 50 in the member 49 and the recess 54 is brought into registration with the passageway 45 to receive an object therefrom. The recesses 53, 54 are in diametric opposed relation and the wheel 48 moves 180° between its aforesaid positions.

The wheel 48 is moved as aforesaid by a shaft 55 splined thereto and journaled in sleeve-like extensions provided by the casing side walls 42. The shaft is received in a housing 56 which is substantially U-shaped and is indented at its inner end to receive an extension on the adjacent wall 42 of the casing structure, as shown in Fig. 4. The housing 56 abuts and is closed by the bottom wall 57 of the chamber 16, which bottom wall is an extension of the wall 17. Between the walls 17 and 18 the housing 56 is provided with a cover plate 58 having a flange 59 generally rectangular in plan positioned in an opening in the outer wall 18 of the refrigerator box. The shaft 55 and housing 56 therefor are thus beneath the bottom wall 57 and project outwardly of the box as shown in Fig. 4. As shown in Fig. 1, the base 21 is recessed to receive the casing structure 41, a portion of the latter projecting into the chamber 16. However, the disposition of the shaft 55 and casing 56 beneath the wall 57 in cooperation with the laterally extending flanges 60 of the casing 75

structure 41 prevents any appreciable variation in temperature by reason of the opening in the box to accommodate the shaft 55 and casing 56.

The shaft 55 is adapted for oscillation and for this purpose there is provided a casing, generally designated by the numeral 61, having an attaching part 61' bolted to the flange 59. As shown more particularly in Fig. 7, the casing 61 has a cylinder 62 in which a piston 63 is reciprocated by compressed air under control of valve means 64 communicating with a source of supply (not shown), the valve means being operated by a lever 65. The piston 63 has a stem 66 to which is secured a rack 67 meshing with a pinion 68 non-rotatably secured to the shaft 55. The rack and pinion are so related as to turn the shaft 55 and dispensing wheel 48 180° in response to movement of the piston 63 in each direction.

In order to retard movement of the dispensing wheel 48 by the aforesaid operating means and to variably time the discharge of chilled articles thereby, the shaft 55 is provided with a fluid control means. The casing 61 has a horizontally extending part 69, as shown in Fig. 6, having a bore 20 receiving the shaft 55, this bore being enlarged 25 at the free end portion of the extremity of the part 69, as shown in Fig. 4, into which extends a reduced portion 70 of a hollow extension generally designated by the numeral 71, this extension 30 being secured by screws 72 to the part 69. The extension 71 has a fluid chamber 73 in which the shaft end portion is rotatably received, which end portion includes a head 74 abutting the shoulder at the reduced section. A seal 75 is interposed 35 between the shaft 55 and inner periphery of the reduced portion 70.

The extension 71 has secured thereto by screws 76 a cap 77 having a projection 78 provided with an orifice 79 therethrough, and an 40 adjacent recess in which an end portion of the shaft 55 is received for oscillation. Carried by and movable with the head 74 of shaft 55 is a vane 80 so positioned thereon as to be movable between opposed extremities of the projection 78 45 to thereby force liquid from one side of the projection 78 to the other through the orifice 79 and thus retard movement of the shaft 55 and dispensing wheel 48. A valve 82 threaded into the projection 78 is operable to restrict the orifice 79 and thus adjustably vary movement of the shaft.

The apparatus as illustrated is particularly adapted for chilling ring-shaped valve seat inserts 83 to facilitate assembly thereof in a cylinder block. These inserts are metallic and the contour of the trackways, the passageways and the receiving recesses 53 and 54 in the dispensing wheel are so sized as to permit the passage of these inserts therethrough. The temperature of 55 the chamber 16 is maintained to such a degree as to reduce the thickness of the inserts from approximately .003 to .005 of an inch. The chilled inserts are removed from the outlet 52 and immediately installed.

In order to avoid interruption in the gravity progression of the inserts along the trackways due to frosting of the rings incident to moisture entering the inlet opening 22 into the chamber 16, I have found it advisable to provide means for reducing the amount of moisture which would otherwise be carried into the chamber 16. Referring to Figs. 2, 8 and 9, there is provided at the top of the refrigerator box the heating chamber 26 positioned at the inlet opening 22, which chamber is formed by a box-like member 84 hav-

ing an opening in the top thereof through which the adjacent trackway-forming parts extend. The chamber 26 contains a pair of electrically energized strip heating elements 85 mounted therein and suitably insulated, each having connectors 86 leading to a source of energy, not shown. As shown in Fig. 8, the trackway-forming part 32 is intermediate the elements 85 so that each trackway is adjacent one of the latter.

While the invention is illustrated and described in connection with cooling or chilling valve seal inserts, it will nevertheless be understood that the same is not limited thereto and that in its broad aspects the invention may be employed in connection with articles other than such inserts.

Although but one specific embodiment of the invention has herein been shown and described, it will be understood that various changes in the size, shape and arrangement of parts may be made without departing from the spirit of the invention.

I claim:

1. In an apparatus of the class described, a cooling chamber having inlet and outlet openings for respectively admitting and discharging articles to be cooled, a pair of trackways for guiding articles between said openings in respective predetermined paths through said chamber for cooling thereof, a casing structure intermediate the termini of said trackways and the outlet opening having spaced walls, a divider in said casing structure cooperating with said walls to form passageways respectively registering with said trackways for receiving cooled articles therefrom, said divider having an opening therein and a dispensing member in said divider opening oscillatable between first and second positions and having axially opposite side faces each having a recess therein, one adapted to register with one of said passageways for receiving cooled articles therefrom when said member is in one of its positions and to discharge articles so received to said outlet opening when said member is in the other of its said positions, the other of said recesses being adapted to register with the other of said passageways to receive cooled articles therefrom when said member is in the other of its said positions and to discharge articles so received when said member is in its said one position.

2. In an apparatus of the class described, a cooling chamber having inlet and outlet openings for respectively admitting and discharging articles to be cooled, a pair of trackways for guiding articles between said openings in respective predetermined paths through said chamber for cooling thereof, a casing structure in said chamber intermediate said outlet opening and said trackways having spaced walls, a divider extending into said casing structure cooperating with said walls to form passageways respectively registering with said trackways for receiving cooled articles therefrom and communicating with said outlet, a dispensing wheel in said casing structure oscillatable between first and second positions for alternately passing articles from each of said receiving passageways to an outlet passageway, said wheel having axially opposite faces each provided with a recess adapted to respectively register with a predetermined passageway for receiving articles therefrom, said recesses being so spaced as to be alternately moved into and out of registration with its

predetermined passageway in response to successive movement of said wheel between its said positions, an oscillatable shaft non-rotatably secured to said wheel journaled in said casing structure and having a portion thereof projecting from said chamber, and means connected with the latter portion of said shaft for oscillating the same.

3. In an apparatus of the class described, a cooling chamber having inlet and outlet openings for respectively admitting and discharging articles to be cooled, a pair of trackways for guiding articles between said openings in respective predetermined paths through said chamber for cooling thereof, an oscillatable member having recesses therein in said chamber for alternately dispensing articles from said trackways to said outlet opening, an oscillatable shaft connected with said member and having a part thereof exteriorly of said chamber, power-operated means for oscillating said shaft, a housing receiving said shaft part having a fluid chamber, a partition in the chamber having a fluid metering orifice therethrough, and a vane in said fluid chamber secured to said shaft for oscillation therewith between opposed faces of the partition for displacing fluid through said orifice in opposite directions during the respective strokes of oscillatory movement whereby to retard oscillatory movement of said member under the influence of said power means.

4. In a device of the class described, a refrigerator including a cooled chamber having spaced inlet and outlet openings for respectively admitting and discharging articles to be cooled, a structure supported on said refrigerator and positioned at said inlet opening providing a heated chamber exteriorly of said cooling chamber for decreasing the amount of moisture admitted to said cooling chamber as an incident to the admission into the latter of the articles to be cooled, a pair of trackways extending through said heated chamber and said inlet opening into said cooling chamber for guiding articles to be cooled through said heated chamber and between said inlet and outlet openings, that portion of each of said trackways extending through said heated chamber including an article-receiving slot open at one side thereof, an electrically activated heating element adjacent each of said trackway portions and overlying the said open side thereof, and means for dispensing cooled articles from said trackways to said outlet opening.
